UNITED STATES PATENT OFFICE.

JOHN E. COTTON, OF FAIRFIELD, MAINE.

IMPROVEMENT IN LAP-BOARDS.

Specification forming part of Letters Patent No. **154,126**, dated August 18, 1874; application filed May 20, 1874.

To all whom it may concern:

Be it known that I, JOHN E. COTTON, of Fairfield, county of Somerset, State of Maine, have invented a Lap-Board, of which the following is a specification:

The nature of my invention consists of a lap-board formed like the ordinary lap-board, with the exception of being made of slats of wood attached by means of glue to cloth, thereby rendering the same capable of being rolled up and closely packed when not in use.

In the accompanying drawing, Figure 1 represents a top view of the lap-board; Fig. 2, an end view of the same; Fig. 3, a transverse sectional view; and Fig. 4, a view of the under side of the lap-board.

A is the lap-board, composed of slats of

wood attached to a foundation of cloth. B B are the braces for giving rigidity to the lap-board when in use.

When the board is not in use the braces may be turned back, and the whole rolled up into a compact form to be laid aside.

Having described my invention, I claim and desire to secure by Letters Patent—

A lap-board composed of slats of wood attached to cloth and provided with end braces, substantially as described and shown, for the purpose specified.

JOHN E. COTTON.
